UNITED STATES PATENT OFFICE.

JAMES W. L. JAQUES, OF SALT LAKE CITY, UTAH.

WIRE-HANGER.

SPECIFICATION forming part of Letters Patent No. 644,921, dated March 6, 1900.

Application filed November 27, 1899. Serial No. 738,355. (No model.)

To all whom it may concern:

Be it known that I, JAMES W. L. JAQUES, a citizen of the United States, and a resident of Salt Lake City, in the county of Salt Lake and 5 State of Utah, have invented a new and Improved Wire-Hanger, of which the following is a full, clear, and exact description.

This invention relates more particularly to devices for supporting overhead trolley-wires; 10 but it may be used for suspending other wires or cables.

The object of the invention is to provide a hanger of simple construction that may be readily and quickly applied to hold a wire 15 firmly without bending the hanger and, further, to so arrange the device that it may be moved along a wire when it is desired to change its location.

I will describe a wire-hanger embodying my 20 invention and then point out the novel features in the appended claims.

Reference is to be had to the accompanying drawings, forming a part of this specification, in which similar characters of reference indicate 25 corresponding parts in all the figures.

Figure 1 is a side elevation of a hanger embodying my invention. Fig. 2 is a section on the line 2 2 of Fig. 3, and Fig. 3 is a section on the line 3 3 of Fig. 2.

30 The hanger comprises a casing 1, open at its top and ends, but closed at the bottom 2, and along the inner surface of this bottom 2 the wire 3 is designed to pass. Movable longitudinally in the casing 1 and in opposite directions are clamping-blocks 4 5. These blocks are shown as serrated on their lower ends, so as to grip tightly against the wire 3. However, it is to be understood that the said lower ends may be left perfectly plain.

40 Bolts 6 7 pass through the side walls of the casing 1 and also through slots 8 9, formed through the blocks 4 5, these slots being inclined from their inner ends downward to their outer ends. The inner or adjacent ends 45 of the blocks 4 and 5 are inclined upward and inward, and adapted to engage with these inclined ends is a wedge-block 10, the upper end of which may be variously shaped and to which a link or other suitable suspending device 50 vice 11 may be attached. This block 10 has its sides inclined to correspond to the inclined ends of the blocks 4 and 5, and a bolt 12 passes

through the side walls of the casing 1 and also through a vertical slot 13, formed through the wedge-block 10. All the bolts may be round, 55 square, or any desired shape.

In operation to place the device on a wire the casing 1 is first to be slipped over the wire. The wedge-block 10 may be then placed in position, with the bolt 12 passing loosely through 60 it, and after this the blocks 4 and 5 are to be placed in position, with the bolts 6 7 passing loosely through them. Now by drawing upward on the block 10 or by drawing downward on the wire 3 it is obvious that by the 65 relative movement of the block 10 and the blocks 4 and 5 and because of the bolts 6 and 7 engaging with the upper inclined walls of the slots 8 and 9 the blocks 4 and 5 will be moved outward and into close engagement 70 with the wire, after which the several nuts on the bolts are to be tightened.

It may be sometimes necessary to connect electrically the adjacent ends of two wires with a hanger. I therefore provide the blocks 75 4 and 5, respectively, with openings 14 and 15, adapted to receive the ends of the wires, said ends of course being drawn upward to engage in the openings.

The hanger may be made very light and 80 with very slight projection below the under side of the trolley-wire, so as not to interfere with the passing of a trolley along the wire. Obviously by loosening the several bolts the blocks 4 and 5 may be sufficiently disengaged 85 from the wire to permit the hanger to be moved longitudinally along the wire, which is sometimes found necessary for adjustment, especially where trolley-wires pass around corners.

Having thus described my invention, I 90 claim as new and desire to secure by Letters Patent—

1. A wire-hanger, comprising a casing open at its top and ends, clamping-blocks movable in opposite directions in said casing for engaging with a wire, and a wedge-block for moving the first-named blocks outward, substantially as specified. 95

2. A wire-hanger, comprising a casing, blocks movable longitudinally in said casing 100 and in opposite directions, the inner or adjacent ends of said blocks being inclined upward and inward, and a block having its opposite sides inclined for engaging with the in-

clines of the first-named blocks, the said last-named block having a movement transversely of the first-named blocks, substantially as specified.

5 3. A wire - hanger comprising a casing, clamping-blocks movable longitudinally in said casing and in opposite directions, bolts passing through the side walls of the casing and also passing through slots in the blocks, 10 the said slots being inclined outward and upward, and a wedge-block for engaging with the inner or adjacent ends of the first-named blocks, substantially as specified.

4. A trolley-hanger, comprising a casing, 15 clamping-blocks movable longitudinally and in opposite directions in said casing, bolts extended through slots in said blocks, the slots being inclined upward and outward, a wedge-block movably engaging with the inclined in-

ner ends of the first-named blocks, and a bolt 20 passing through a slot formed in the wedge-block, substantially as specified.

5. A wire - hanger, comprising a casing, clamping-blocks movable in said casing and in opposite directions, the said blocks having 25 holes or openings in their under sides for receiving the ends of wires, and means for moving said blocks longitudinally and at the same time moving the blocks into engagement with a wire, substantially as specified. 30

In testimony whereof I have signed my name to this specification in the presence of two subscribing witnesses.

JAMES W. L. JAQUES.
